UNITED STATES PATENT OFFICE.

THOMAS COLDWELL AND WILLIAM H. COLDWELL, OF NEWBURG, NEW YORK.

LAWN-EDGE TRIMMER.

SPECIFICATION forming part of Letters Patent No. 340,420, dated April 20, 1886.

Application filed March 25, 1885. Serial No. 160,079. (No model.)

To all whom it may concern:

Be it known that we, THOMAS COLDWELL and WILLIAM H. COLDWELL, of Newburg, in the county of Orange, and in the State of New 5 York, have invented certain new and useful Improvements in Lawn-Edge Trimmers; and we do hereby declare that the following is a full, clear, and exact description thereof, reference being had to the accompanying drawings, in 10 which—

Figure 1 shows a view in side elevation of our machine; Fig. 2, a vertical sectional view of the same on line α α of Fig. 1, looking from the front of the machine; Fig. 3, a perspective 15 view of the revolving cutter removed, and Fig. 4 a detail sectional view showing the adjustable means of attaching the handle to the frame-plate.

Letters of like name and kind refer to like 20 parts in each of the figures.

The object of our invention is to provide an improved machine for trimming the borders and edges of lawns which shall not only cut the grass on the edge, but will cut the dirt 25 away and make the border straight and even; and to this end our invention consists in the construction, arrangement, and combination of parts as hereinafter specified.

In the drawings, A designates the main supporting and driving drum, which, as shown, is made tapering or conical in shape. The larger end of the drum is open, and from the inner side of the closed smaller end thereof a rigid cylindrical hollow shaft or gudgeon, B, 30 extends outward axially through the drum to such open end. As shown, this shaft or gudgeon is preferably made in one piece with the drum. The disk-shaped frame-plate C, fitting within and closing the larger open end of the 35 drum, is provided on its inner side with the central hollow hub or sleeve, D, in which is journaled the shaft or gudgeon B on the drum. Around the gudgeon, at its point of attachment to the smaller end of the drum, is formed the 40 shoulder E, against which the end of the hub or sleeve D on plate C abuts. The frame-plate and the drum are held firmly together, with the gudgeon B journaled in the hub D, by the bolt F, passing through the plate B', forming the 45 smaller end of the drum, the gudgeon or shaft B, and the frame-plate. The head F' of the 50 bolt sets in a recess, G, formed in the outer

side of the frame-plate, so that it shall be out of the way and not project beyond the face of the plate. The outer face of the smaller end 55 of the drum is also recessed at H, to receive the nut I on the threaded end of the bolt. When this nut is tightened up, the frame-plate and drum will be drawn toward each other until the end of the hub or sleeve D abuts 60 against the shoulder E around the base of the gudgeon or shaft B. Below the hub D the frame-plate is provided on its inner side with a second hollow boss or rigid sleeve, K, extending inward nearly to the smaller end of 65 the drum. In this boss is journaled the shaft L, which carries on its inner end a pinion, M, meshing with an internal gear, N, on the drum, and on its outer end beyond the frame-plate 70 the revolving cutter O, to be described more fully.

A fixed knife, P, is attached to the frame-plate by means of screws p so as to project below the lower edge of the plate and the drum or roller A. As shown, this knife is 75 attached to the plate in the rear of the revolving cutter-shaft L, and is so set that its edge inclines downward and forward to a point below the cutter-shaft. It is preferably of such length and so inclined that its 80 end comes vertically below the axis of such shaft. The knife is not parallel to the face of the frame-plate, but is set at an angle thereto, being inclined downward and outward therefrom. As the machine is run forward this 85 knife will then cut the lawn edge so that it will be beveled instead of square. This is very desirable, as the border or edge will then keep its shape better than if its face were left perpendicular, as by a square cut. 90

Attached to the frame-plate near its upper edge, preferably by a bolt, R, as shown, is the angled bracket S, which from its attaching portion is bent outward from the plate and then downward. The outer and lower arm, 95 S', of the bracket, which, as shown, stands at a sufficient distance from the frame-plate to admit the revolving cutter between it and the plate, is provided with a conical ended or pointed screw, T, tapped through it in line 100 with the axis of the cutter-shaft L. The pointed inner end, T', of this screw engages the end of such shaft, a center notch being preferably, but not necessarily, made in the shaft

end for receiving the screw-point. Upon the screw outside of the bracket-arm S' is provided the jam-nut T², for locking the screw from rotation in the ordinary and well-known way. The revolving cutter O consists of the central hub, O', for attachment to the cutter-shaft, and the radial blade-arms O² O² O² O². Four of these are shown; but more or less of them can be used, as desired, without departure from our invention.

The outer sides or backs of the cutter-arms are made substantially at right angles to the axis of rotation of the cutter, while the inner sides or edges, o o o o, of the arms are made inclined outward to correspond with the outward incline of the fixed knife, so that as each blade or arm is brought down by the revolution of the cutter to act in conjunction with the fixed blade its edge will shear close to the edge of such fixed blade throughout its length. The hub O' extends inward along the shaft L and projects into a rabbet in the plate around the shaft-hole.

In order to clear away and throw outward the cut grass or dirt, the forward faces, o' o' o' o', of the cutter-blades O O O O do not stand at right angles to the plane of rotation of the cutter, but are inclined from their outer sides forward and inward. As each cutter arm or blade then comes down to act with the fixed blade to cut the grass and dirt on the lawn edge, the inclined face of the arm striking the cut dirt or grass will throw it outward, so as to leave the face of the lawn edge clear and clean cut.

The fixed cutter-blade is preferably made of such length as to project slightly below the lower or outer ends of the edges of the revolving cutter-blades.

By means of the bearing-screw T the cutter-shaft and revolving cutter thereon can be adjusted endwise toward the stationary cutter to take up or compensate for wear.

On the edge of the frame-plate, to the rear of the point of attachment of the bracket S to the plate, is a disk-shaped extension, U, offset to clear the edge of the drum A, and having the annual series of radial corrugations U' around its edge. The end of the handle V, which can be of wood or metal, is clamped and forced up against these corrugations by means of the bolt W, passing through the handle and a central hole in the extension, and having its head bearing against the back of the extension, and a nut screwed on its outer end bearing against the outer side of the handle. With this construction, if the nut be loosened, the handle can be adjusted by swinging it up or down on the bolt as a pivot. The nut is then tightened up again, so as to cause the corrugations on the exten-

sion to bite or cut into the inner side handle on opposite sides of its pivotal point. The handle will thus obviously be most firmly held at the angle to which it is adjusted.

65

As the roller or drum A is made conical or tapering and the cutting apparatus is situated at the larger end of it, as the machine is pushed along, with the drum resting on the lawn, the fixed knife will by the tendency of the roller 70 to turn the machine inward be hugged up close to the lawn edge, and the tendency to side draft caused by the cutters will be counteracted. Our machine, constructed and operating as described and shown, then cuts a 75 bevel edge upon the lawn, and leaves such cut edge clean and clear of the cut grass or dirt, and while doing its work can be easily and perfectly guided to cut the edge on the desired line because of its freedom from side 80 draft. It is simple, and can be taken apart and put together easily and quickly, and while the various parts can be adjusted to take up wear there is nothing complicated about it to get out of order.

85

Having thus described our invention, what we claim is—

1. In combination with the frame-plate, substantially at right angles to the supporting and driving roller, the fixed knife attached to 90 the plate, and extending downward and outward at an angle thereto, the revolving cutter revolving on an axis at right angles to the plate, having the forward sides of its blades inclined outward and rearward, and the inner 95 sides adapted to shear close to the fixed knife, substantially as and for the purpose described.

2. The revolving cutter consisting of the hub and the blades attached thereto, having their forward faces or sides inclined outward 100 and rearward, and the lines of their inner sides inclined outward from the hub, substantially as and for the purpose described.

3. In combination with the taper roller and the frame-plate, substantially at right angles 105 to the axis of the roller, the fixed knife attached to the plate, and extending downward and outward at an angle thereto, the revolving cutter revolving on an axis at right angles 110 to the frame-plate, having the forward sides of its blades inclined outward and rearward, and the inner sides adapted to shear close to the fixed knife, substantially as and for the purpose described.

In testimony that we claim the foregoing we 115 have hereunto set our hands this 14th day of March, 1885.

THOMAS COLDWELL.
